L. STROHACKER

LOOM REED

Filed May 15, 1922

Inventor:

Louis Strohacker,
by Charles Sherway
his Atty.

UNITED STATES PATENT OFFICE.

LOUIS STROHACKER, OF FREEPORT, ILLINOIS, ASSIGNOR TO STRUCTO MANUFACTURING COMPANY, OF FREEPORT, ILLINOIS, A CORPORATION OF ILLINOIS.

LOOM REED.

Application filed May 15, 1922. Serial No. 560,909.

To all whom it may concern:

Be it known that I, LOUIS STROHACKER, a citizen of the United States, and a resident of Freeport, Stephenson County, and State of Illinois, have invented certain new and useful Improvements in Loom Reeds, of which the following is declared to be a full, clear, and exact description.

This invention relates to loom reeds and its principal objects are to simplify the construction of loom reeds; to reduce the cost of manufacture thereof; to simplify the work of assembling the parts, and to otherwise improve thereon. With these and other objects and advantages in view, this invention consists in the several novel features of construction, arrangement and combination of parts hereinafter fully described and claimed.

The invention is clearly illustrated in the accompanying drawing, in which:

Fig. 1 is a view, partly in side elevation and partly in central, longitudinal section through a loom reed, embodying a simple form of the present invention; Fig. 2 is a vertical, cross section taken on the line 2—2 of Fig. 1, and Fig. 3 is a perspective view of a fragment of one of the dent holding bars employed.

Referring to said drawing, which illustrates a simple embodiment of the invention, the loom reed comprises two side frame members 4, 4, two spaced, horizontal, dent holding bars 5, 6, extending therebetween, the dents 7, and means for spacing the dents apart, and for securing the parts together. The side frame members 4 are channel shaped, and are placed with the channels facing each other. The dent holding bars 5, 6, are preferably formed of sheet metal folded up along their median lines to provide structures having somewhat the form of a U shape, in cross section, the two sides of which are bent into arcuate or substantially semi-circular parts 10, the concave sides of which face each other and form a substantially cylindrical like channel 8 that runs from end to end of the dent holding bars. The dents 7 are preferably formed of flat wire and extend into the channels 8 of the dent holding bars, where they are spaced apart by spacers, here shown as comprising discs 9 which are contained in the channels 8 of the dent holding bars. Located in the

channels of the side frame members 4, between the end dents 7^a and members 4, are blocks 11, 12, which, if desired, may be of sufficient length to fill in the spaces between the end dents and side frame members.

To compensate for any unevenness or variation in the spacing of the dents, coiled compression springs 13 may be interposed in the channels 8 of the dent holding bars 5, 6, at one or both ends thereof, between the end dents and side frame members. Long bolts or threaded tie rods 14, and nuts 15 threaded thereon, connect the side frame members 4, and as a preference the tie rods extend through the hollows of the dent holding bars 5, 6. The U bends of said bars 5, 6, are spaced away from the arcuate portions 10 to leave flat parallel side portions 16 and the tie rods extend through the hollows between the said flat portions and between the U bends and extreme end of the dents. When the nuts 15 are screwed up, the side frame members 4 are brought to bear against the ends of the dent holding bars 5, 6, and the filler blocks 11, and springs 13, and the dents 7 and discs 9 are therefore firmly clamped in place. To reinforce the frame, a substantially U shaped brace 17 is inserted at the lower ends of the side frame members 4, the legs 18 of which extend up into the channels of the side frame members. The loom reed is pivotally mounted on loom frame members 19, and is actuated in the usual manner well known to those skilled in the art to which this invention pertains.

More or less variation as to the exact details of construction is possible without departing from the spirit of this invention; I desire, therefore, not to limit myself to the exact form of the construction shown and described, but intend, in the following claims, to point out all of the invention disclosed herein.

I claim as new and desire to secure by Letters Patent:

1. A loom reed comprising two pivotally supported, side frame members; grooved horizontal members abutting against said side frame members and extending crosswise therebetween with their grooves facing each other, dents extending between said horizontal members with their end portions entering the grooves thereof, spacing discs

- 2
- between said reeds, spacing members between the reeds and side frame members, and tie rods, with means thereon, for holding said side frame members in contact with 5 said horizontal members, with the dents held under pressure between the side frame members.
2. A loom reed comprising two pivotally supported, side frame members; grooved 10 dent holding bars abutting against said side frame members and extending crosswise therebetween with their grooves facing each other, spaced dents extending between said bars with their end portions entering the 15 grooves thereof, pressure members interposed between the dents and side frame members, and tie rods extending between and connecting said frame members.
3. A loom reed comprising two pivotally 20 supported, side frame members, grooved dent holding bars abutting against said frame members and extending crosswise therebetween, with their grooves facing each other, spaced dents extending between said 25 bars with their end portions entering the grooves thereof, resilient members interposed between the dents and side frame members, and tie rods with means thereon for holding said side frame members in contact with 30 said dent holding bars, with the
- dents held under pressure between said side frame members.
4. A loom reed comprising two pivotally supported, side frame members, upper and lower dent holding members substantially 35 U shaped in cross section, the sides thereof having outwardly bulging portions, forming with each other a channel, dents extending from one dent holding member to the other with their end portions passing through 40 said channels, spacing discs in said channels, between said dents, and means for clamping said dents and discs together between said side frame members.
5. A loom reed comprising two pivotally 45 supported, side frame members, upper and lower dent holding bars, substantially U shaped in cross section, the sides of which are bulged outwardly to form a channel therebetween, dents extending between said 50 bars with their end portions passing through said channels, spacing discs located in said channels between the dents, and tie rods extending through the hollows of said bars along the ends of said dents, there being 55 nuts upon said tie rods for clamping the side frame members upon the dent holding bars, and clamping said dents and discs between said side frame members.

LOUIS STROHACKER.
